STREET SWEEPING MACHINE

Oliver J. Arnett, Santa Ana, Calif.

Application December 2, 1940, Serial No. 368,268

6 Claims. (Cl. 15—86)

The present invention relates to improvements in street sweeping machines.

An object of the invention is the provision of a street sweeping machine of generally improved construction.

Another object of the invention is to provide a sweeping machine equipped with brush means mounted to conform to irregularities in the street surface.

A further object of the invention is the provision of a street sweeping machine which is highly efficient in operation.

Still another object of the invention is the provision of a sweeping machine of the aforesaid character which is compact and durable in construction and not unduly expensive to produce.

Other objects and advantages of the invention will become apparent as the description progresses.

In the accompanying drawings forming a part of this specification and in which like numerals are employed to designate corresponding parts throughout:

Figure 1 is a top plan view of the machine with parts removed and other parts broken away to illustrate interior construction.

Figure 2 is a fragmentary top plan view of the driver's seat and adjacent structure.

Figure 3 is an enlarged fragmentary section taken on line 3—3 of Figure 4.

Figure 4 is a right side elevational view partly in section.

Figure 5 is a detail elevational view of the rear brush and adjacent structure.

Figure 6 is a similar view showing the brush worn down to substantially decreased diameter.

Figure 7 is an enlarged sectional view taken approximately on line 7—7 of Figure 8.

Figure 8 is a section taken approximately on line 8—8 of Figure 7.

Figure 9 is a similar section taken on line 9—9 of Figure 7.

Figure 10 is a left side elevational view of the machine with parts in section.

Figure 11 is a fragmentary side elevational view of the front of the machine showing the hopper in dumping arrangement.

Figure 12 is a transverse sectional view taken on line 12—12 of Figure 4.

Figure 13 is a similar view taken on line 13—13 of Figure 4.

Figure 14 is a fragmentary top plan view of the elevator inlet.

Figure 15 is a detail elevational view of one of the elevating blades.

Figure 16 is an elevational view of part of one of the blade guiding levers.

5 Figure 17 is a fragmentary detail view of a connecting knuckle for the blades.

Figure 18 is a detail section taken approximately on line 18—18 of Figure 15 showing the guide lever connected to the blade.

10 Figure 19 is a sectional view through the casting sections of the elevator showing said sections in separating relation.

Figure 20 is a fragmentary view through the same showing the sections in assembled relation.

15 Figure 21 is a perspective view showing one of the blades with its associated guide and actuating mechanism, and

Figure 22 is a fragmentary elevational view showing the hopper dumping cam mechanism.

20 Referring to the drawings, wherein for the purpose of illustration is shown a preferred example of the invention, F generally designates the frame of the machine having a U-shaped

25 rearward portion 10 which is connected to a rear axle housing 11 having conventional axle shafts 12 mounted therein for driving the rear wheels

13. The differential, indicated at D, is driven through the medium of an upwardly directed

30 shaft 14 journaled in a tubular housing 15 and carrying, at its upper end, a bevel pinion 16 in mesh with a complementary pinion 17 secured integral with the bevel drive gear 18. This latter gear is secured on a transversely extending

35 shaft 19 journaled in a housing 20 supported in upstanding brackets 21. The gear 18 is also in mesh with a pinion 22 connected with the countershaft of a conventional transmission T disposed at the rear of a drive motor M having

40 a forwardly extending gear shift lever L. The motor M is supported on horizontally extending frame bars 23 to one of which are connected laterally projecting brackets 24 supporting a seat

25 mounted at the rear of a steering wheel 26 secured on the upper end of a vertically disposed

steering shaft 27. The lower end of this steering shaft connects with any preferred known type of steering mechanism S connected with the end spindles 28 of a pair of front wheels 29,

45 said spindles being mounted to turn at the ends of a transverse front axle 30. This axle is secured to the depending bracket elements of a transversely extending forward frame bar 31, the

50 ends of which connect with the forward portions

55 of side frame bars 32.

Pivotedly supported on the machine forwardly of the motor is an elevator assembly of approximately circular form comprising a base section of pan-shaped formation 33 having a flat bottom 34 and an inclined side wall 35 providing an increasing taper from the bottom 34 outwardly thereof. The top of this elevator section is shaped to form an annular marginal flange 36 extending inwardly from the top edge of the circumferential wall 35. At the bottom 34, within the section 33, is formed an annular rib 37 concentric with a center opening 38 therein. This base section 33 is assembled in complementary relation with a cover section 39 in the form of a flat circular head chamber formed at the inner wall 40 with a frusto-conical neck 41 shaped at the outer end to form a cylindrical flange 42 adapted to be rotatably fitted about the rib 37. At the intermediate portion of the conical neck 41 is formed a web 43 provided with a central opening 44 and having a collar 45 bolted thereto. The inner circular wall 40 of this section is provided at angularly spaced intervals with curved slots 46, the purpose of which will be described hereinafter.

These sections are releasably secured in interfitting assembly by a diametrically arranged clamp structure embodying a top section 47 disposed to extend across the upper casing section 39 and a bottom section 48 extending across the bottom of the base casing section 33, these clamp sections being detachably secured by bolts 49 at opposed ends thereof. In axial relation with the casing sections 33 and 39 the clamp sections are provided with bearings 50 in which are journaled the end portions of a shaft 51. To this shaft is secured the inner hub portion 52 of a spider frame having four radial arms 53 and to the ends of which is secured an approximately circular track forming ring 54 arranged within the cover section 39. Spaced inwardly from the spider arms 53 within this section is a plate 55 in the form of a disk keyed to the shaft 51 in a plane parallel with the spider. To the top face of this disk are secured by screws 56, a plurality of, in the present example 8, arms 57 arranged tangentially on the disk and having their outer portions projecting therefrom. To the outer end of each arm 57 is connected, by a knuckle pivot joint embodying complementary sections 58 and 59 shown to advantage at Figure 17, a lever 60 of obtuse angular formation. To one longitudinal side face of the angular extension 61 of each lever 60 is secured, by screws 62, the upper slotted head part 63 of a T-shaped connecting element having a right angular slotted body bar 64 and, at the end opposed to the head 63, a bracket bar 65. The intermediate body portion 64 of this T member is designed to extend through one of the slots 46 while the lower bracket portion 65 is secured to one side of an elongated blade 66. This blade is formed at its inner end with a right angular flange 67. To the bottom and outer edges of the blade body 66 is fastened a strip 68 of flexible and resilient material such as rubber. On the outer arm portion 61 are mounted, in parallel positions, a pair of complementary rollers 69 rotatably supported on suitable spindles and adapted, in assembly, to roll upon the opposed faces of the superposed track 54 as shown to advantage at Figure 21. The collar 45 secured to the web 43 of the outer elevator casing is keyed to the shaft 51 so that this casing section is rotated with the shaft.

This assembled elevator mechanism is actually

formed so that the base section is semicircular at the elevated portion while the depending portion is tapered, having converging side walls 70 which merge into a straight horizontally disposed lower wall portion 71, the front wall flange 36 being open at this lower portion to provide an inlet opening or mouth 72. The guide track 54 is likewise of irregular shape at the lowermost portion, as shown at Figure 7, having straight converging lower portions 73 merging into an ogee portion 74 at the bottom. Thus, the track is peculiarly shaped to guide the blades, during their revolution within the fixed base portion of the casing, so that the bottom longitudinal and outer edges of the rubber strip 68 will move in resilient contact with the bottom wall 34 and the peripheral wall 35 of this section, as shown to advantage at Figures 7 and 8.

On the outer end of the rotary shaft 51 is secured a bevel gear 75 in mesh with a right angular bevel pinion 76 secured on a transversely extending shaft 77. The gears 75 and 76 are housed in a gear casing 78 one side of which connects with a tubular housing 79 enclosing the shaft 77. The outer end of this housing extends to and connects with a casing 80 at one side of the frame enclosing a bevel pinion 81 on shaft 77 in mesh with a bevel gear 82 secured to a forwardly directed inclined shaft 83 mounted in a housing 84 and having fixed on its forward end a bevel pinion 85 engaging a bevel gear 86 in a casing 87. On the intermediate portion of the shaft 77 is secured a bevel gear 88 in mesh with a bevel pinion 89 fixed on the forward end of a rearwardly directed shaft 90 extending through a housing 91. At the rear end of the shaft 90 is secured a bevel gear 92 meshing with a bevel pinion 93 in a casing 94. This bevel gear 93 is secured on the outer end of the transversely extending shaft 77 to complete the drive from the power take-off to the elevator mechanism and the countershaft 83.

Through the casing 87 is extended a transverse fixed shaft 95 secured to the casing by a collar and nut connection 96 and having a tubular shaft 97 rotatably fitted thereon. This latter shaft is secured to the gear 86 and makes driving connection with a pulley 98 over which is trained a drive belt 99. The shaft 95 extends through bearings 100 secured to the forward frame extensions 32 and supports thereon a sleeve 101 between the bearings 100. The major length of the sleeve 101 is connected, by welding or the like, with a bottom of a hopper receptacle 102 mounted at the front of the machine frame and essentially of rectangular shape. The upper inner portion of the hopper is provided with an inlet opening 103 about which is formed an arcuately-shaped hood 104. This hopper is normally seated on the forward frame bars but is tilttable forwardly, as shown at Figures 10 and 11, about the axis of the shaft 95. With this in mind, a segmental cam 106 is secured to a projecting end of the sleeve 101, this cam having an arcuate edge 107 arranged to engage a roller 108 at the end of a push rod 109. The rear end of this rod is secured to a plunger 110 mounted to reciprocate in a cylinder 111 normally retracted by a coil spring 112 and adapted to be actuated by compressed air or any other preferred manner to swing the cam from its normal downward position, as shown in Figure 22, to an upwardly directed position as shown at Figure 10 wherein it turns the sleeve 101 and tilts the hopper forwardly as shown at Figures 10 and 11.

At the front of the hopper is provided an angular cover 113 connected to the hopper body 102 by a hinge 114 and normally held in closed position by a spring pressed latch 115. This latch is releasable through the medium of a cable 116 operable from a position conveniently accessible to the machine operator to free the cover or door 113 so that it swings from the end of the hopper when the latter is in tilted arrangement in order that the contents of the hopper may be conveniently dumped therefrom.

The elevator housing and the associated drive gearing are supported on the machine by bearing brackets 117 secured to opposed sides of the frame. The bearing of one of these brackets serves to support the transversely extending shaft housing 19 while the complementary bracket serves to support a pivot pin 118. The sections 47 and 48 which clampingly engage the elevator casing assembly are formed, at each end of the frame member 47, with bearing brackets 119, one of which rotatably engages the pin 118 while the other is pivotally mounted on the shaft housing 19 adjacent the bearing of the support bracket 117.

On the transmission shaft 14 is secured a bevel pinion 120 in mesh with a bevel gear 121 secured on a laterally extending shaft 122. To the other end of this shaft is connected a pinion 123 in mesh with a gear 124 secured on the rear end of a longitudinally extending drive shaft 125. This latter shaft extends forwardly at one side of the frame and is enclosed in a housing 126. On the forward end of shaft 125 is secured a bevel pinion 127 in mesh with a bevel gear 128 fixed on the outer end of a transversely disposed stub shaft 129. On the opposite end of this stub shaft is secured a pinion 130 in mesh with a gear 131 fixed on the upper end of a depending shaft 132, the lower end of which is secured by a disk thereon to the head of a circular brush 133 disposed to assume an approximately horizontal position when operative. This brush is disposed at the forward right hand side of the machine and is adapted to effectively sweep the right hand gutter or the corner at the curbstone edge of the street.

In order that this gutter or curbing brush may be raised to a non-sweeping position the casing 134 enclosing the bevel gears 123 and 124 is formed with a bearing sleeve 135 rotatably fitted on the end portion of the housing 136 enclosing the shaft 122. This sleeve is enlarged to clear and abut a collar 137 fixed on the end of the housing 136 by a screw 138 to form a pivot connection which will allow vertical adjustment of the shaft housing 126. The forward portion of this housing 126 is supported on a roller 139 rotatably mounted in the lower end of an angular lever 140 fulcrumed intermediate its ends on a pivot supported in a bracket 141. A link 142 pivotally connects the lever 140 with the upper end of a bell crank lever 143 pivoted on the frame by a pivot 144 and having the outer end of its short arm connected to the lower end of a tension spring 145. The upper end of this spring connects with the eye of a screw 146 supported by a nut 147 threadedly engaging the same and bearing on an angular bracket attached to the machine frame. This lever mechanism normally supports the brush under the tension of the spring 145 and enables elevation thereof upon rearward movement of the lever 140, to clear obstacles or to render the gutter brush inoperative.

5   Mounted transversely at the rear of the machine is a cylindrical brush 148 making draft connection with the frame through the medium of a pair of complementary arms 149 having their forward ends pivotally connected to the frame by a pivot connection 150 and their rear ends pivotally engaging trunnions 151 projecting axially from the brush core. At one side of the brush is secured a bevel gear 152 disposed to mesh with a bevel pinion 153 secured on the forward end of a shaft 154. This shaft is of the slidably extensible type embodying a pair of telescopic non-circular sections having secured to the rear end a bevel pinion 155 in mesh with a driving pinion 156. This latter pinion is secured to the outer end of a stub shaft 157 journaled in the casing 158 and having fixed on its inner end a bevel pinion 159. The pinion 159 is mounted to mesh with a pinion 160 secured on the outer end of a shaft 161, driven through the medium of bevel gears 162 from the rear drive axle shaft of the machine. The shaft 154 is enclosed in a telescopic extensible housing 163 having rotatable connection with the gear housing 158 to permit vertical angular movement of the shaft. This mechanism provides means for rotatably driving the brush in a counter-clockwise direction as shown at Figures 4 and 5.

30   To longitudinally extending frame bars at each side of the brush 148 are connected a pair of complementary arcuate support members 164 disposed in vertical planes. Each of these members is pivotally attached to the frame by a pivot connection 165 and is formed at the bottom end with an angular foot 166 bifurcated to carry a street engaging roller 167. The upper end of each of these members is provided with a bearing 168 formed with an interiorly threaded bore through which is extended an adjustable screw 169 which may be locked in set position by a locking nut 170. To an eye at the inner end of the screw 169 is fastened the outer end of a coiled tension spring 171 disposed so that its inner hooked end engages the apertured ear of a collar 172 rotatably fitted on each trunnion of the brush. This structure serves to form a spring support for the rear brush of the machine.

45   Pivots connected to a triangular web 173 secured in rearwardly extending position to each side of the elevator opening, by a pivot 174, is a tapered shoe plate 175 arranged in a vertical plane at each side of the brush and indented at the forward end to form a tongue portion 176 which projects beneath the elevator casing, as shown to advantage at Figures 4, 5 and 6. Each of these shoe plates has a longitudinal taper diminishing toward the rear end and shaped to form a straight slide edge 177 at the bottom thereof. These shoes function to direct sweepings from the end portions of the brush 148 into the mouth or inlet of the elevator.

50   The extensible shaft connection for driving the rear brush enables vertical movement of the brush to follow inequalities in the street surface and maintains the bottom contact area of the brush at substantially uniformly shaped relation with the inlet of the elevator even though the brush become greatly reduced in diameter, due to wear, as best illustrated at Figure 6. As shown therein the spring suspension of the brush may be maintained when the brush has become appreciably worn by loosening the nut 170 for downward extension of the screw 169, from time to time.

65   75   The belt 99 driven from the pulley 98 is trained

over a pulley 178 fixed on a shaft 179 journaled transversely on and extending through the rear portion of the hopper 182. On this shaft, within the hopper, is secured a sleeve carrying a plurality of radial elongated vanes 180 disposed, relative to the inlet of the hopper, so as to throw the material to the forward portion of the hopper. The bottom right side of the hopper is shaped to provide a cavity 181 therein to afford clearance for the elevation of the circular brush 133.

At the rear of the frame is mounted a tank 182 adapted to contain a supply of water which may be sprinkled in any preferred manner to lay the dust.

During sweeping operation of the machine the horizontally disposed brush 132 sweeps the gutter and angular corner portion at the curbing and throws the sweepings laterally into the path of the main rear sweeper, this front brush rotating in a counter-clockwise direction as viewed from Figure 1. The cylindrical rear brush, rotated in a counter-clockwise direction as viewed from Figure 4, throws the sweepings, such as dirt, leaves and the like, into the lower inlet opening of the rotary elevating apparatus. In this casing the rotating blades 66, moving in the direction shown at Figure 7, carry the sweepings upwardly through the marginal passage in the stationary casing section 33 and discharge the same through the outlet 183 in the upper portion thereof and the registering opening 183 in the hopper wherein the rotary vanes 180 throw the material toward the forward portion of the hopper.

The extensible and pivotally movable shaft connections for driving the brushes enable vertical movement thereof for effective sweeping of uneven surfaces of a street while the spring suspension of the brushes provides highly suitable brush contact without injury to the bristles.

Thus, the machine presents an exceptionally compact structure for sweeping, elevating and carrying dirt and the like from streets, the hopper formation and arrangement affording exceptionally large capacity for carriage of the sweepings. This construction is not unduly complicated but is durable and simple to operate.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a street sweeping machine having a brush at the rear portion and a sweepings receiving hopper on the forward portion, an approximately circular shaped casing mounted on the frame between the brush and the hopper, the said casing being disposed in a plane transverse of the frame and inclined longitudinally from the vertical and having a flattened inlet opening at the lower portion disposed to receive sweepings from the brush and having an outlet at the upper portion discharging into the hopper, a plurality of blades mounted to rotate in the said casing about an axis coincident with the axis of the casing to convey matter arcuately therein from the inlet to the outlet, and means for rotatably actuating the said blades so that each portion thereof is maintained in contact with the casing.

2. In a street sweeping machine, a wheeled

frame, a pair of pivoted arms extending rearwardly from the frame, a rotary brush journaled in the outer ends of the said arms, an extensible drive connection for rotating the brush, a pair of arcuate members pivotally connected to the frame and disposed concentrically with relation to the brush axis, a roller mounted at the lower end of each of the said arcuate members, and an adjustable suspension spring mounted at the top of the arcuate member and supporting the said brush.

3. In a street sweeping machine, a wheeled frame, a street sweeping brush mounted transversely on the said frame, a hopper supported on the frame, a flat elevator casing mounted in oblique position on the frame, the said casing having the major upper portion of circular contour and the lower peripheral portion shaped to form a transversely flattened bottom part having tapering sides merging into the upper circular portion, the bottom rear portion being open to form an inlet and the upper forward portion open to form a discharge outlet, a plurality of blades mounted in the said casing and movable in a marginal path therein, means for revolving the said blades for moving sweepings from the bottom inlet to the upper outlet of the casing, and a guide frame in the said casing associated with the said blades adapted to guide the blades in their movement so that the outer edges of the blades will permanently contact with and follow the irregular peripheral contour of the wall of the casing.

4. In a street sweeping machine, a wheeled frame, a pair of arms pivotally connected with the frame and extending longitudinally thereof, a cylindrical brush extended transversely of the frame and having its ends journaled in the free ends of the said arms, a pair of arcuate support members pivotally connected with the frame in vertical arrangement having street engaging rollers mounted at the lower ends thereof, an adjustable support element carried by the upper end of each of the said arcuate members having supporting connection with the said brush, and means for rotating the brush.

5. In street sweeping apparatus having a wheeled frame, a rotary street sweeping brush having end trunnions, a pair of vertically disposed support frame sections pivotally connected with the said wheeled frame and supported on the surface over which the apparatus operates, and a support element adjustably mounted at the upper portion of each support frame section having connection with a trunnion at the end of the brush for vertically adjusting the said brush.

6. In street sweeping apparatus having a wheeled body frame, a cylindrical brush having axial trunnions projecting from the ends thereof, a pair of brush support frame sections pivotally connected with the body frame in upstanding positions, each of the said frame sections having a ground engaging support roller, a screw member mounted in the upper portion of each frame section having support connection with each trunnion of the brush for adjustably supporting the brush with relation to the frame sections, a vertically swinging arm pivotally connected with the body frame and having a trunnion of the brush rotatably journaled in its outer end, and means for rotating the said brush.

OLIVER J. ARNETT.
